UNITED STATES PATENT OFFICE.

HERMAN A. SIEVERT, OF THE UNITED STATES ARMY.

SADDLE.

1,069,822.

Specification of Letters Patent. Patented Aug. 12, 1913.

Application filed August 16, 1910. Serial No. 577,406.

To all whom it may concern:

Be it known that I, HERMAN A. SIEVERT, of the United States Army, residing at Fort D. A. Russell, in the county of Laramie and 5 State of Wyoming, have invented certain new and useful Improvements in Saddles, of which the following is a specification.

My invention relates to certain new and useful improvements in saddles and its principal object is to provide a saddle of novel 10 construction which, when fastened upon the back of a horse or other animal, will adjust itself to conform with the contour thereof, and which, while the animal is in motion, 15 will yield without displacement to allow free action of its muscles.

Further objects of my invention reside in the provision of means on the saddle whereby the saddle-blanket is held against slipping under the saddle, and in providing a 20 novel method of suspending the stirrups whereby their position relative to the front and rear of the saddle may be readily adjusted to accommodate riders of different 25 physical proportions or to ease the position of the occupant of the saddle during long rides.

Other objects of minor importance will 30 fully appear in the following description in which reference is had to the accompanying drawings in the various views of which like parts are similarly designated and in which

Figure 1, represents a top view of the saddle, Fig. 2, a perspective side-elevation of 35 the same, Fig. 3, a transverse section taken along the line 3—3 Fig. 1, and drawn to an enlarged scale, Fig. 4, a similar section along the line 4—4 Fig. 1, the side bars of the saddle having been brought closer together, Fig. 40 5, an enlarged longitudinal section along the line 5—5 Fig. 1, Fig. 6, a fragmentary side view of the front end of the saddle showing the knuckle connection between the side bars and the pommel, and Fig. 7, a fragmentary 45 section showing a modified construction of the pommel.

Referring to the drawings by numerical reference characters, my improved saddle is composed of two side bars 2, identical in 50 construction and configuration, which are pivotally connected at the extremities of two curvilinear yokes 3 and 4, which being respectively disposed near the front and rear ends of the saddle, provide effective substitutes for the pommel and the cantle of the 55 saddles now in common use.

Each of the two side bars 2 is composed of a flanged plate, preferably made of metal of sufficient flexibility to permit them to conform longitudinally and transversely with 60 the contour of the back of the animal upon which it is fastened and to yield in accordance with its muscular action, the longitudinal flexibility of the plates having been increased by the omission of part of the 65 flanges at their longitudinal edges as has been shown in Figs. 4 and 5 of the drawings. In this connection I wish it understood that while the flanges on the plates afford convenient means for the fastening of the 70 material with which the side bars are usually covered, the same may be omitted and the fastening effected by a different method.

The side bars 2, may if so desired, be connected at their juxtaposed longitudinal edges 75 by a lacing 5 and they are formed in their lower surfaces with corrugations 6 and apertures 7 which prevent the saddle blanket from slipping between the saddle and the surface upon which it is fastened and which 80 furthermore, strengthen the bars and provide ventilation to the spaces between them and the saddle blanket.

The side bars 2 are provided with coverings 8 which may be composed of leather or 85 other suitable material and which are secured along the edges of the bars either in direct contact with their upper surfaces or upon an interposed padding 9 made of cork, 90 felt or other desirable substance.

The yokes 3 and 4 are preferably composed of leather-covered metal and they may be made in one piece as shown in Figs. 1 to 6 of the drawings, or they may consist of two lapping sections 10, as shown in Fig. 7, 95 95 which being detachably connected by means of bolts 12, permit their longitudinal extension.

The pivotal connections between the yokes and the side bars are effected by the provision of corresponding axially aligned knuckles 13 and 14 which being respectively secured at the ends of the yokes and upon the upper surfaces of the respective side-bars, are movably connected by means of 105 pins 15.

The stirrups 16 are suspended from the front portion of the saddle by the use of a continuous leather 17, which passing freely across the upper surfaces of the side bars, 110 in proximity to the pommel 3, depend at opposite sides thereof and, after having been

passed through slots at the upper ends of the stirrups, are detachably secured by means of buckles 18, to D-rings 19, preferably secured at the extremities of the pommel 3.

The above described arrangement of the stirrup leather permits changing of the position of the point of suspension of the leather by merely placing the portion thereof which 10 is supported across the side bars, at the opposite side of the pommel 3, as has been indicated in dash-dot lines in Fig. 2 of the drawings.

The cinch, or surcingle by means of which 15 the saddle is secured upon the back of an animal, is composed of a girth 20 which is provided at its opposite ends with the usual straps 21 and the buckles 22. The girth 20 passes, freely, across the upper surfaces of 20 the side bars 2, and in case the latter are covered, beneath the coverings 8, so that, when the saddle is secured in place upon the animal by fastening the straps 21 below its belly, the free engagement of the girth 25 with the upper surfaces of the flexible bars, will compel the latter to adjust themselves and conform to the contour of the animal's back.

The side bars 2 and the yokes 3 and 4 are, 30 as usual, provided with fastening devices, such as the rings 23, to secure the equipment or pack of the rider, especially for military purposes.

As the operation and advantages of my 35 improved saddle have been referred to at intervals, in the course of the foregoing description, it will only be necessary to outline them very briefly at this point.

The transverse and longitudinal flexibility of the two side bars 2 and their independent, pivotal connection with the yokes 3 and 4, allow them to bend in conformity with the contour of the back of the animal, and to yield to its muscular and articular 45 action while in motion, when secured in place by means of the surcingle which passes freely across their upper surfaces as hereinbefore described. The space between the

juxtaposed longitudinal edges of the side bars, whether connected by the lacing or not, 50 permits free movement of the vertebrae of the animal, the pivotal connection of the bars adapts the saddles for use on both broad-backed and slender animals, the corrugations and perforations prevent slipping 55 of the saddle blanket and the novel method of arranging the stirrup leather affords ready means for changing the position of the stirrups relative to the front and rear of the saddle for the greater comfort of the 60 rider.

Having thus described my invention what I claim and desire to secure by Letters-Patent is:—

1. A saddle comprising a pommel, side 65 bars independently movably connected therewith, a stirrup leather placed loosely across the upper surfaces of said bars, its ends being secured to said pommel, and stirrups suspended from said leather at opposite sides of the saddle.

2. A saddle, comprising in combination, a pair of flexible metallic side-bars joined to bring their adjacent longitudinal edges into relatively close movable spaced relation, and 75 means passing around both of said bars and adapted to press them inwardly into conformity with the shape of a horse's back on each side of the spine without pressure on the latter.

3. A saddle, comprising in combination, a pair of flexible side-bars joined to bring their adjacent longitudinal edges into relatively close movable spaced relation, a surcingle passing freely and entirely over said 85 side-bars and adapted to press them into conforming contact with the shape of a horse's back on each side of the spine, and means on said bars to prevent slipping of the latter on a saddle blanket.

In testimony whereof I have affixed my signature in presence of two witnesses.

HERMAN A. SIEVERT.
